Filed Feb. 2, 1962, Ser. No. 170,556
1 Claim. (Cl. 242—75.43)

This invention relates to a novel control system for automatically maintaining constant tension in fabrics passing through a dyeing jig.

In the prior art of dyeing jigs, it is well known to shuttle a length of fabric between two beam rolls in a guided path through a dyeing vat, until the desired degree of dyeing has been achieved. In such jigs, it is usual to employ a drive motive means which can be clutched selectively into torque engagement with either roller, which then becomes the wind up roll. The undriven roll becomes the pay off beam roll and is arranged to be retarded by a control torque supplied from a manually-adjusted drag brake on the pay off side.

The variables with which the manual operator of such a drag brake has to contend include the reciprocally varying diameters of the pay off and take up rolls during the fabric transfer, and the oscillation loads imposed by the static and dynamic centrifugal unbalance forces caused by the gravitational accumulation on one side of a roll of a mass of liquid dye while a roll is standing between reversals.

As a consequence of this difficulty for the operator manually to maintain constant tension, there will result inhomogeneity in the dyeing as well as a variation in the pick count of the fabric. Conversely, the uniformity of the product will be dependent on the skill of the operator.

The present invention obviates these difficulties and provides a high degree of uniformity in the tension on the fabric in spite of the foregoing variables, by utilizing a drag brake pneumatically-controlled by a closed servo loop of the fabric in which the error signal is generated by the displacement from a predetermined pull position of a pneumatically-tensioned dancer roll whose position reflects the tension obtained in the fabric passing through the dyeing jig.

It is the principal object of the present invention to provide a reliable and automatic means to maintain constant tension in the fabric passing through a dyeing jig.

It is another object of the invention to relieve the operator of a dyeing jig from the responsibility of having to maintain constant tension in the fabric passing through this jig.

It is still another object of the invention to provide automatic means in a dyeing jig for producing uniform dyeing results.

It is a further object of the invention to provide a design of servo control for dyeing jigs which utilizes available pneumatic valve and actuator components.

It is a still further object of the invention to provide a sensitive, mechanically stable means responsive to web tension for controlling a web transport system.

For further objects and a better understanding of the present invention reference may be had to the following detailed description taken in conjunction with the accompanying drawings, in which

FIGURE 1 is a perspective view of the preferred embodiment of the dyeing jig invention as seen from the manual control station side and with the dyeing vat broken away to clarify the fabric path,

FIG. 2 is a transverse view in elevation through the line 2—2 of FIG. 1, showing the dancer roll servo feed back roller with its parallel motion gear racks and pneumatic tension bias cylinders,

2

FIG. 3 is a partial perspective view of the subject dyeing jig as seen from the drive and pneumatic brake side and from the opposite side end viewed in FIG. 1,

FIG. 4 is a sectional view in elevation and taken on line 4—4 of FIG. 2 showing the fabric path,

FIG. 5 is an elevational view taken on line 5—5 of FIG. 2 showing the feed back proportioning valve cam actuated by the dancer roll, and

FIG. 6 is a schematic diagram of the pneumatic servo circuit of this invention associated with the operating dyeing jig parts.

Referring now to the drawings, 8 designates a fabric web which is being withdrawn from a pay off beam roll 9 and drawn onto a wind up roll 11. It is to be understood that the foregoing designations of pay off roll and wind up roll is applicable at the illustrated moment and will be reversed between rolls 9 and 11 at each reversal of the passage of the fabric 8.

A set of idler guide rollers 12, 13, 14, 16, 17 and 18, all journaled together with rolls 9 and 11, in two end frame members 19 and 21, guide the fabric 8 through a dye vat trough 22 containing a liquid dye 23.

An idler floating pneumatically-tensioned dancer roll 24 intervenes between idler rolls 14 and 16 in the fabric circuit. This dancer roll 24 comprises a sleeve which is freely journaled on a dancer roll shaft 26, FIG. 2. Shaft 26 has a spur gear 27 secured to it at each end. Each spur gear 27 engages a gear rack 28 secured to each of the end frame members 19 and 21 by support members 29 and 31 respectively, FIGS. 1, 2, 3 and 5. The foregoing rack and pinion constraint, 27—28, forces shaft 26 and its dancer roll 24 to move vertically, kept horizontal and always parallel to the axes of fabric rolls 9 and 11 and guide rollers 12, 13, 14, 16, 17 and 18.

Dancer roll shaft 26, FIGS. 1 and 2, is embraced at each end by a ball bearing 29 secured to a piston rod 31. This piston rod 31 and its associated piston form the linear actuator for each of two pneumatic cylinders 32 secured to frames 19 and 21 by supports 33. When pneumatic pressure is applied to cylinders 32 through pneumatic supply line ducts 34 and micrometer adjusted flow control valve 34' which meters the flow of input air to cylinders 32 but does not restrict the back pressure flow of air to the exhaust port on regulator 36, FIG. 6, the dancer roll 24 is forced upward to increase tension in the fabric web 8. Conversely, for a given air pressure in cylinders 32, an increasing fabric tension will force dancer roll 24 downward.

The vertical position of dancer roll shaft 26 is sensed by a pressure controller 36 whose control lever 37 acts as a cam surface, FIG. 5, so that as dancer shaft 26 rises along racks 28, it forces lever 37 to rotate counterclockwise about its pivot 38. The motion of lever 37 is communicated to the pressure controller 36 by means of a plunger 39.

The pressure controller 36 is of the well known type of pneumatic control in which an impressed pressure source is modulated so that the output pressure is made to be proportional to the displacement of lever 37. This action is schematically shown in FIG. 6 in which an input pressure supplied by line 41 is movably applied through a valve block 42 at a location determined by plunger 39 acting against spring 43. An output valve block 44 having an extended port 46 receives the input pressure from line 41 when in proper registration with input block 44. Valve block 44 is positioned by the equilibrium between spring 47 and the force exerted on a piston 48 by a pneumatic cylinder 49 due to the pressure delivered to it from a duct 51.

The action of this pressure controller 36, FIG. 5, is as follows: When cam lever 37 is forced inward by the rising of dancer roll 24 it displaces valve block 42 to the left

against spring 43 so as to open inlet source pressure duct 41 to port 46 in block 44 and an outlet duct 52. The pressure in duct 52 therefore rises until the communicating duct 51 delivers enough pressure to the cylinder 49 to force output block 44 against spring 47 far enough to the left to shut off the communication between blocks 42 and 44. Thus, a pressure level in line 52 is always servo-slaved to the position of the dancer roll 24.

An adjustment screw 53 is provided to adjust the equilibrium output pressure in line 52 to any predetermined value when lever 37 is undisplaced by dancer roll shaft 26. Valve means 44 thus automatically vents line 52 when its pressure exceeds the pressure demanded by the position of lever 37.

Beam roll 9 is provided with a brake 56 and a pneumatic braking cylinder 57, while beam roll 11 is provided with a brake 58 and a pneumatic braking cylinder 59, FIG. 3. Duct lines 61 and 62 control the pressure in cylinders 57 and 59 respectively. A needle valve 52' regulates the air flow to and from cylinders 57 and 59 to buffer major corrections in air pressure requirements. This prevents over controlling. Pressure controller 36 is mounted, FIG. 5, by the adjustable support 61' on one of the structural members 29 so as to afford an adjustment of the transfer function between dancer roll shaft 26 position and the pressure control function of lever 37.

The selective drive system for this dyeing jig generally indicated at 62', FIG. 6, is a conventional differential drive including a reversible motor 63, FIGS. 2 and 3, a drive belt 64, a driven pulley 66, and a differential gear box 67. Conventional means, not shown, are provided for selectively engaging beam roll 11 or beam roll 9 as the wind up roll.

Hand wheels 68 and 69, FIG. 1, are provided for retracting the outboard journals 70 and 71 from engagement with rolls 9 and 11, respectively for removal and insertion of rolls of the fabric 8 into the dyeing jig. For manual non-automatic control of the tension in fabric 8, separate air control panels 73 and 74 are respectively provided to control the respective braking cylinders 57 and 59.

The panel 73 is provided with a three-way, on-off manual pneumatic valve 76 for activating panel 73, a manually adjustable pressure controlling valve 77, and a pressure gauge 78. Similarly, panel 74 is provided with a three-way, on-off manual pneumatic valve 79 for activating panel 74, a manually adjustable pressure controlling valve 81, and a pressure gauge 82.

When either panel 73 or 74 is under command of the dyeing jig operator, manual operation of either pressure controlling valve 77 or 81 determines the braking torque of brake 56 or 58.

When the system is on automatic servo control according to the present invention, an automatic control panel 83, FIGS. 3 and 6, is provided, and includes a four-way selector pneumatic valve 84 for choosing control of brake 56 or 58, a manually adjustable pressure regulating valve 86 and pressure gauge 87 for setting the predetermined tension in fabric 8 imposed by cylinders 32, and a manual three-way venting valve 88 which is used in the transfer of control between panels 73 and 74 and the automatic panel 83.

Two shuttle valves 91 and 92 associated with automatic control panel 83, FIG. 6, allow the shifting between manual control panels 73 and 74 and automatic panel 83 without pneumatic sneak circuits or interferences.

The pneumatic circuit of this system may be followed in FIG. 6. An air pressure supply source 93 is provided which connects via pneumatic lead duct 41 to panels 83, 73, 74 and to the proportional pressure controller 36. Controller 36 has the adjustment screw 53 which sets the minimum pressure delivered to control line 52 when the dancer roll shaft 26 is in its lowest position.

In the positions of the valves shown, the system is in its automatic mode under control of automatic panel 83

and dancer roll 24. When the manual three-way venting valve 88 is in the "on" position, a direct feed through lines 52 and 94 is made which communicates to pressure gauge 89 and the input of four-way direction selector valve 84. When venting valve 88 is in the "off" position, line 52 is blocked and line 94 is vented as shown by the conventional valve symbols illustrated.

In the position of direction selector valve 84 shown, the controlled input air pressure on line 94 representing the servo feed back error signal, is being distributed by selector valve 84 to lead 96 and, via shuttle valve 92 and lead 97 and through a needle or throttle valve 52' which buffers quick change of air pressure in brake cylinders 57 and 59 to the brake cylinder 57 which is associated with the correct roll 9 to be retarded for the running direction shown. For the reverse condition to that shown, selector valve 84 would be in its opposite condition in which controlled pressure from line 94 would be distributed via line 98, shuttle valve 91, and line 99 to brake cylinder 59 on roll 11. Selector valve 84 automatically vents the brake cylinder 57 or 59 which is not being pressurized.

The input air supply pressure lead 41 to automatic control panel 83 is regulated by the manually set regulator 86 and after being read by pressure gauge 87 is impressed via leads 34 and through micrometer flow control valve 34' on the dancer roll tension cylinders 32. The manual control panel 73 passes air from the input line 41 through regulator 77 to gauge 78 and on-off valve 76 shown in the "off" position thereby venting line 101 leading to shuttle valve 92.

Similarly, manual control panel 74 passes air from the input line 41 through regulator 81 to gauge 82 and on-off valve 79 shown in its "off" position thereby venting line 102 leading to shuttle valve 91.

The purpose of the two shuttle valves 91 and 92 is to seal off those control panels which are not being used. Thus, each shuttle valve 91 or 92 has two inputs 98, 102, or 96, 101, and one output 97 or 99 leading to control braking cylinder 57 or 59. Whichever shuttle input is pressurized, or has the higher pressure, causes the other input lead to be sealed, thereby preventing unwanted pneumatic sneak circuits.

For this reason, it is necessary in order to vent the inputs 96 and 98 by moving valves 84 and 88 to the "off" position, opposite that shown, in order to surrender control of the system from automatic control panel 83 to manual control panels 73 and 74. Conversely, valves 76 and 79 must be moved to their "off" position shown thereby venting lines 101 and 102 before shuttle valves 91 and 92 will surrender control back to automatic control panel 83.

The automatic operation according to the present invention is as follows: With the valves 76, 79, 84 and 88 in the positions shown, and the minimum air pressure to be delivered by the pressure controller 36 to an empirically predetermined valve as read on gauge 89, a minimum braking drag is effected which will allow the dancer roll 24 to maintain control under the worst operating conditions of beam roll unbalance. Pressure regulator 86 is now opened until a pressure, as read on gauge 87, and applied to tension cylinders 32 is attained which lifts the dancer roll 24 and its fabric loop to some intermediate position on gear racks 28.

The selective motor drive system 62 is then energized to apply drive torque to roll 11. As the fabric 8 moves through vat 22, it will be subjected to the uniform tension supplied by cylinders 32 and regulator 86. If any factor such as roll diameter variation, unbalance, or friction tends to vary this set tension the dancer roll 24 will immediately reflect this change and apply a corrective braking on cylinder 57 due to the feed back of control lever 37.

Thus, an increasing tension will cause dancer roll 24 to descend thereby diminishing the pressure on brake 56,

while a decrease in fabric tension will cause roll 24 to rise and increase braking on roll 9.

While various changes may be made in the detailed construction, it shall be understood that such changes shall be within the spirit and scope of the present invention as defined by the appended claim.

What is claimed is:

In a dyeing jig, a supporting end frame member, fabric web beam rolls journaled between the frame members for reverse rotation, selective reversible mechanism to drive either of said rolls as wind up roll and placing torque upon the other roll and adapted for manual and automatic operation, a dye vat disposed between the end frame members beneath the beam rolls and adapted to contain liquid dye, idler guide rollers journaled between the end frame members to guide the fabric web through the dye vat, an idler floating dancer roll means intervening between the idler rolls in the fabric circuit and including a dancer roll shaft having a spur gear secured to each end thereof and a sleeve freely journaled upon the shaft, a vertically-extending gear rack mounted on each end frame member and meshing with a spur gear to keep the dancer roll means parallel to the idler guide rollers while moving vertically, a journal bearing embracing each end of the dancer roll shaft, a pneumatic cylinder device mounted on each end frame and having a piston rod to the upper end of which a journal bearing is secured and the dancer roll means, regulated pres-

sure means for supplying air under pressure to the pneumatic cylinder devices to extend their piston rods and to force upwardly the dancer roll whereby to increase the tension in the fabric web and to sense the downward force of the fabric upon the dancer roll, a fluid pressure impressed controller adjustably mounted upon one end frame member having cam lever means engaging the floating dancer roll means to be operated thereby and, said fluid pressure impressed controller serving to modulate its output pressure in proportional response to the displacement of the cam lever and the dancer roll, a pneumatically-operable braking device associated with each of the beam rolls, means for supplying air under pressure from the regulated pressure supply means to the pneumatically-operable beam roll braking devices, said regulated pressure supply means having a manually adjustable air regulator for setting the dancing roll to modulate the drag torque of a brake and to fix the tension of the fabric to be maintained by the dancer roll.
